(57) **CLAIM**

I claim the ornamental design for a heart box, as shown and described.

DESCRIPTION

FIG. 1 is a perspective view of a heart box, showing my new design in a folded configuration;

FIG. 2 is a front elevational view of FIG. 1;

FIG. 3 is a rear elevational view of FIG. 1;

FIG. 4 is a left-side elevational view of FIG. 1;

FIG. 5 is a right-side elevational view of FIG. 1;

FIG. 6 is a top plan view of FIG. 1;

FIG. 7 is a bottom plan view of FIG. 1; and,

FIG. 8 is a front elevational view thereof, illustrated in a flat configuration.
